UNITED STATES PATENT OFFICE

LAWRENCE P. DWYER, OF WINNETKA, ILLINOIS, ASSIGNOR TO C. A. DUNHAM COMPANY,
OF MARSHALLTOWN, IOWA, A CORPORATION OF IOWA

REMOVABLE BASEBOARD FOR CONCEALED RADIATORS

Application filed June 12, 1931. Serial No. 543,873.

This invention relates to certain new and useful improvements in a removable baseboard section for covering, or partially covering, the inlet opening leading to a concealed 5 radiator positioned within a wall recess.

The importance of keeping all of the space in a building available for use, as well as the desire to avoid having heating equipment spoil the interior decorative effect of a 10 room, has made concealed radiation very desirable. To accomplish this result the radiator is installed in a recess in the building wall and delivers its heat principally by means of convection air currents, the air flowing 15 into and through the recess in contact with the radiator and being discharged into the room after being heated. A preferred radiator assembly of this type is disclosed and claimed in my copending application, Serial 20 No. 543,871, filed June 12, 1931.

This type of radiator unit may comprise a sheet metal casing which is mounted within the wall recess and is provided with a lower inlet opening (usually adjacent the floor) and 25 an upper outlet opening, these openings extending through the inner sheathing of the building wall. The radiator is mounted within the casing and air currents flow in through the lower inlet opening, thence up in 30 contact with the radiator and the heated air is discharged through the upper outlet opening. In the preferred example disclosed in my copending application above referred to, the radiator may be inserted into the casing or 35 removed therefrom through the lower inlet opening.

As disclosed in said copending application the inlet and outlet openings are both covered by suitable removable grilles which partially 40 cover and protect these openings without materially interfering with the flow of the air currents through the casing, and which may be made to conform to the decorative effect of the room. In some installations it is 45 not desirable to provide a grille for the lower inlet opening, but it has been found preferable to leave an opening entirely free so that the inlet may be kept clean without the necessity for removing the grille. It is desirable 50 that this clear opening be smaller than the

main inlet opening through which the radiator is inserted or removed. According to the present invention a section of the usual baseboard which is positioned at the base of the side walls of the room, said section being 55 of sufficient length to cover the main inlet opening leading to the casing, is made removable and is provided with a smaller air inlet opening in its lower central portion. Means are provided engageable with the bottom edge and rear face of the removable baseboard section for holding this section in normal position, said means being concealed but readily accessible through the air inlet opening in the removable section. 65

The principal object of this invention is to provide an improved removable baseboard section such as briefly described hereinabove and disclosed more in detail in the specifications which follow. 70

Another object is to provide a removable baseboard section with matched beveled end portions so as to apparently form a continuous portion of the room baseboard when in position. 75

Another object is to provide improved spring means mounted within the radiator casing or wall recess for holding the removable baseboard section in place.

Another object is to provide improved 80 turnbuckle mechanism positioned within the radiator casing or wall recess for holding the removable baseboard section in position.

Other objects and advantages of this invention will be more apparent from the following detailed description of certain approved forms of mechanism constructed according to the principles of this invention. 85

In the accompanying drawings:

Fig. 1 is a perspective view of a section of 90 the room wall showing the radiator assembly installed and the removable baseboard section in position.

Fig. 2 is a transverse vertical section 95 through the radiator assembly with the baseboard section in position.

Fig. 3 is a front elevation of the lower portion of the radiator assembly with the baseboard section removed.

Fig. 4 is a horizontal section taken sub- 100

stantially on the line 4—4 of Fig. 3 but showing the removable baseboard section in position.

Fig. 5 is a rear elevation of the removable baseboard section.

Fig. 6 is a vertical section through the lower portion of the assembly showing an alternative means for holding the removable baseboard section in position.

- 10 The sheet metal casing which houses the radiator comprises an upper section 1 having an open lower end, and a lower section 2 having an open upper end, these two sections telescoping together as indicated at 3 so that 15 the vertical height of the assembled casing may be varied according to the needs of the individual installation. The casing is housed within a wall recess 5 between two adjacent vertical studs 6. The upper casing member 1 20 is cut away across the upper portion of its front wall to form an air outlet opening, this opening being surrounded by a flanged collar 7 which projects through the inner sheathing 8 (the lathing and plaster) of the building 25 wall, and a removable grille 9 is positioned in this opening. A damper 10 carried by the grille 9 and adjustable by means of a knob 11 mounted in the grille controls the flow of air through the radiator casing.
- 30 The bottom portion of the front wall of the lower casing section 2 is cut away across its entire width to form an inlet opening adjacent the floor through which the air to be heated enters, and through which the radiator 35 12 may be inserted or removed. The upper side and ends of this inlet opening are enclosed by a flanged collar 13 which projects through the wall sheathing 8.
- 35 The radiator 12 (which is disclosed more 40 specifically and claimed in my copending application referred to hereinabove) comprises a pair of end headers 12' connected by a plurality of radiating tubes 14 having spiral fins 15 thereon to increase the radiating 45 surface. An inlet fitting or valve 16 is connected with the lower portion of one header 12', and an outlet trap 17 is connected with the lower portion of the other header, the supply and return pipes of the heating 50 system leading from these members 16 and 17 through the ends or bottoms of the casing. The inlet fitting 16 and the trap 17 are positioned within the overall length of the radiator, and when the steam supply and return 55 pipes are disconnected, the entire radiator assembly may be withdrawn from the casing through the inlet opening 18 in the building wall. The radiator is normally held in position within the casing by means of removable bolts 19 engaged with the end walls 60 of the casing through lugs 20 formed on the bottoms of the respective headers 12', and by means of springs 21 mounted in the upper portion of the lower casing section 2 and engageable with the upper end portions of the

headers. By simply removing the bolts 19 the radiator may be withdrawn through opening 18, and it may be replaced by reversing these steps.

As disclosed in my copending application above referred to, the inlet opening 18 is closed by a removable grille somewhat similar to the upper grille 9 which closes the outlet opening. According to the present invention the baseboard 22 which is fitted against the lower portion of the side wall adjacent the floor 23 of the room is continued across the inlet opening 18 to form a closure for this opening. As will be clear from an inspection of Figs. 2 and 3 of the drawings, the inlet opening 18 is of somewhat less height than the baseboard 22 so that the baseboard extends above the upper edge of the opening.

A removable baseboard section 24 is provided of somewhat greater length than the total length of the inlet opening 18 leading to the casing. Preferably the ends of this removable section 24 are beveled inwardly from the outer surface as indicated at 25 so as to mate with correspondingly outwardly beveled surfaces 26 on the ends of the adjacent fixed sections of the baseboard. Preferably the removable baseboard section should be cut out of the continuous piece used for the adjacent fixed baseboard sections so that the grain will match at the beveled joints. In this way the appearance of a continuous and uninterrupted baseboard is obtained. The central lower portion of the removable section 24 is cut away as indicated at 27 to provide an opening for the inlet air. The floor 23 extends continuously beneath this opening so that the lower portion of the wall recess may be easily cleaned out. At the same time no material portion of the radiator assembly is visible through this relatively shallow opening, and the ornamental appearance of the room is not seriously impaired.

In order to strengthen the removable baseboard section 24 and prevent warping thereof, a metallic reinforcing plate 28 may be secured to the rear face of the section adjacent the upper edge of the air inlet opening 27. Of course, a more extensive reinforcing plate could be used if desired, but a strip such as indicated at 28 will ordinarily be sufficient. It will be noted that this reinforcing plate 28 will lie within the inlet opening 18 so as not interfere with the flush positioning of the removable baseboard section 24 against the building wall.

It is desirable that this baseboard section 24 be easily removable so that the full extent of opening 18 will be available for removing, adjusting or repairing the radiator assembly. The quarter-round molding strips 29 which are positioned at the juncture of the baseboard 22 with the floor 23 are continued out in front of the removable section 24 to the edges of the opening 27 therein.

Similar molding strips 30 are positioned on floor 23 inside the opening 18 at the two sides of the opening 27 so as to form slots in which rest the wider end portions of the 5 removable baseboard section 24. A plurality of eyes or hooks 31 are secured in the rear face of section 24 adjacent the upper edge of opening 27. Opposite these hooks in the rear sheet metal wall of casing section 2 are 10 cut pairs of openings 32 so as to form intervening metal strips 33 (see Fig. 3). Tension springs 34 are formed with hooks 35 at their ends so as to be removably engaged with the hooks 31 on the removable baseboard section 15 and with the strips 33 in the rear wall of the casing. Preferably the anchoring means 33 in the rear casing wall are positioned somewhat below the hooks 31 on the removable baseboard section so that the pull of the 20 springs 34 will be exerted downwardly and rearwardly, thus securely holding the removable baseboard section in place.

It will now be apparent that by inserting a hand through the opening 27 in section 24 the springs may be unfastened from the hooks 31 and the removable section 24 may then be lifted out so as to uncover the entire inlet opening 18 and permit access to the radiator. If the radiator is to be removed, 30 the springs 34 will preferably be unhooked from the strips 33 in the rear casing wall so as not to be in the way of the radiator while it is being removed or replaced. It is for this reason that the strips 33 are utilized as 35 an anchoring means for the springs, thus avoiding the use of any unnecessary projections on the rear wall of the casing 2. Except for this objection any other form of hooks or eyes could be mounted in the casing wall 40 to anchor the springs 34. It will be apparent that the engaging means 31 and 35 on the removable section 24 and springs 34 may be both hooks, or either one may be a hook and the other an eye as may be most convenient. The terms "hooks" or "eyes" as 45 used in the claims which follow are intended to cover any such alternative constructions.

If fasteners which exert a constant holding action are desired instead of the resilient 50 fasteners 34, turnbuckles 36 may be substituted for the springs as indicated in Fig. 6. These turnbuckles may be engaged with the removable section 24 and the rear wall of the casing in exactly the same manner as the 55 springs 34, and the turnbuckles may be screwed up in a well known manner so as to firmly clamp the removable baseboard section in place. It will be apparent that access to the turnbuckles for screwing the same into 60 position or unscrewing them when the baseboard is to be removed, is possible through the air inlet opening 27. Other forms of fastening means might be used, the essential 65 feature being that these fastening means are concealed behind the removable baseboard

section and within the radiator casing, but are sufficiently accessible through the air inlet opening so that they may be readily unfastened to permit the removable baseboard section to be withdrawn.

It will be apparent that if the lower portion or rear wall of the sheet metal casing were not used, the rear ends 35 of the fasteners for securing the removable baseboard section in place could be attached in any suitable manner to the wall at the back of the wall recess 5. The fasteners would function in the same manner as already described.

I claim:

1. In combination with a concealed radiator assembly comprising a casing positioned within a wall recess there being an inlet opening leading to the recess through the inner wall sheathing of the room adjacent the floor, and a radiator mounted within the casing, a removable baseboard section forming a portion of the continuous baseboard of the room, said removable section covering the inlet opening and formed with a smaller opening for permitting air to enter the casing, and concealed means engaged with the rear of the baseboard section for holding the baseboard section in position over the inlet opening, said means being accessible through the opening in the removable section. 95

2. In combination with a concealed radiator assembly comprising a casing positioned within a wall recess there being an inlet opening leading to the recess through the inner wall sheathing of the room adjacent the floor, and a radiator mounted within the casing, a removable baseboard section forming a portion of the continuous baseboard of the room, said removable section covering the inlet opening and formed with a smaller opening for permitting air to enter the casing, and means housed within the casing and accessible through the opening in the removable section for holding the section in position over the inlet opening. 100

3. In combination with a concealed radiator assembly comprising a casing positioned within a wall recess there being an inlet opening leading to the recess through the inner wall sheathing of the room adjacent the floor, and a radiator mounted within the casing, a removable baseboard section forming a portion of the continuous baseboard of the room, said removable section covering the inlet opening and formed with a smaller opening for permitting air to enter the casing, a plurality of eyes secured on the rear face of the removable section adjacent the opening therein, and springs anchored at their inner ends at the rear of the recess and removably attached at their front ends to the eyes. 115

4. In combination with a concealed radiator assembly comprising a casing positioned within a wall recess and having an inlet opening projecting through the inner wall 130

- sheathing of the room adjacent the floor, and a radiator mounted within the casing, a removable baseboard section forming a portion of the continuous baseboard of the room, said removable section covering the inlet opening and formed with a smaller opening for permitting air to enter the casing, a plurality of eyes secured on the rear face of the removable section adjacent the opening therein, the casing comprising a rear sheet metal wall from which adjacent pairs of openings are cut to form intervening metal strips, and springs having hooked ends adapted to be engaged with the strips and eyes respectively to hold the baseboard section in position over the inlet opening.
5. In combination with a concealed radiator assembly comprising a casing positioned within a wall recess and having an inlet opening projecting through the inner wall sheathing of the room adjacent the floor, and a radiator mounted within the casing, a removable baseboard section forming a portion of the continuous baseboard of the room, said removable section covering the inlet opening and formed with a smaller opening for permitting air to enter the casing, a plurality of eyes secured on the rear face of the removable section adjacent the opening therein, the casing comprising a rear sheet metal wall from which adjacent pairs of openings are cut to form intervening metal strips, and turnbuckles engaged at their ends with the strips and eyes respectively.
35. 6. In combination with a concealed radiator assembly comprising a casing positioned within a wall recess there being an inlet opening leading to the recess through the inner wall sheathing of the room adjacent the floor, and a radiator mounted within the casing, a removable baseboard section forming a portion of the continuous baseboard of the room, said removable section covering the inlet opening and formed with a smaller opening for permitting air to enter the casing, a plurality of eyes secured on the rear face of the removable section adjacent the opening therein, and turnbuckles secured at their inner ends adjacent the rear wall of the recess and removably attached at their outer ends to the eyes.
7. In combination with a concealed radiator assembly comprising a casing positioned within a wall recess there being an inlet opening leading to the recess through the inner wall sheathing of the room adjacent the floor, and a radiator mounted within the casing, a removable baseboard section forming a portion of the continuous baseboard of the room, said removable section covering the inlet opening and formed with a smaller opening for permitting air to enter the casing, concealed means removably engaging the rear of the section, and means for holding the baseboard section in position over the inlet opening.
8. In combination with a concealed radiator assembly adapted to be positioned within a wall recess, said recess having an upper outlet opening and a lower inlet opening adjacent the floor and projecting through the inner wall sheathing of the room, a removable baseboard section forming a portion of the continuous baseboard of the room, said removable section covering the inlet opening and formed with a smaller opening for permitting air to enter the wall recess in which the radiator is positioned, means secured to the floor for removably receiving and holding the lower edge portion of the removable baseboard section and means for removably securing the upper portion of the removable section to an inner wall of the recess.
9. In combination with a concealed radiator assembly adapted to be positioned within a wall recess, said recess having an upper outlet opening and a lower inlet opening adjacent the floor and projecting through the inner wall sheathing of the room, a removable baseboard section forming a portion of the continuous baseboard of the room, said removable section covering the inlet opening and formed with a smaller opening for permitting air to enter the wall recess in which the radiator is positioned, and means positioned within the wall recess and accessible through the smaller opening for removable attachment to the baseboard section for holding the section in position over the inlet opening.
10. In combination with a concealed radiator assembly comprising a casing positioned within a wall recess there being an inlet opening leading to the recess through the inner wall sheathing of the room adjacent the floor, and a radiator mounted within the casing, a removable baseboard section forming a portion of the continuous baseboard of the room, the ends of the removable section being beveled inwardly from the front face of the section to mate with the outwardly beveled ends of the adjacent fixed baseboard sections, said removable section being of a length sufficient to cover the inlet opening and formed with a smaller opening for permitting air to enter the casing, and concealed means accessible through the smaller opening for holding the baseboard section in position over the inlet opening.
11. In combination with a concealed radiator assembly comprising a casing positioned within a wall recess and having an inlet opening projecting through the inner wall sheathing of the room adjacent the floor, and a radiator mounted within the casing, a removable baseboard section forming a portion of the continuous baseboard of the room, the ends of the removable section being beveled inwardly from the front face of the section to

mate with the outwardly beveled ends of the adjacent fixed baseboard sections, said removable section covering the inlet opening and formed with a smaller opening for permitting air to enter the casing, a plurality of eyes secured on the rear face of the removable section adjacent the opening therein, the casing comprising a rear sheet metal wall from which adjacent pairs of openings are cut to form intervening metal strips, and springs having hooked ends adapted to be engaged with the strips and eyes respectively to hold the baseboard section in position over the inlet opening.

tral portion to form an air inlet of less length and height than the main inlet opening, molding strips secured to the floor between which the lower portions of the removable section at the sides of the air opening are engaged, a plurality of eyes secured to the rear face of the section adjacent the opening therein, and springs secured at their rear ends adjacent the rear wall of the recess and removably attached at their front ends to the eyes. 70 75

15. In combination with a concealed radiator assembly comprising a casing positioned within a wall recess there being an inlet opening leading to the recess through the inner wall sheathing of the room adjacent the floor, and a radiator mounted in the casing and removable through the inlet opening, a removable baseboard section forming a portion of the continuous baseboard of the room, said removable section covering the inlet opening and being cut away in its lower central portion to form an air inlet of less length and height than the main inlet opening, molding strips secured to the floor between which the lower portions of the removable section at the sides of the air opening are engaged, a plurality of eyes secured to the rear face of the section adjacent the opening therein, and turnbuckles secured at their rear ends adjacent the rear wall of the recess and removably attached at their front ends to the eyes. 80 85 90 95

16. In combination with a concealed radiator assembly comprising a casing positioned within a wall recess and having an inlet opening projecting through the inner wall sheathing of the room adjacent the floor, and a radiator mounted in the casing and removable through the inlet opening, a removable baseboard section forming a portion of the continuous baseboard of the room, said removable section covering the inlet opening and being cut away in its lower central portion to form an air inlet of less length and height than the main inlet opening, molding strips secured to the floor between which the lower portions of the removable section at the sides of the air opening are engaged, a plurality of eyes secured to the rear face of the section adjacent the opening therein, the casing comprising a sheet metal wall from which adjacent pairs of openings are cut to form intervening metal strips, and springs having hooked ends engageable with the strips and eyes respectively.

17. In combination with a concealed 120
radiator assembly comprising a casing positioned within a wall recess and having an inlet opening projecting through the inner wall sheathing of the room adjacent the floor, and a radiator mounted in the casing and removable through the inlet opening, a removable baseboard section forming a portion of the continuous baseboard of the room, said removable section covering the inlet opening and being cut away in its lower central por- 125 130

tion to form an air inlet of less length and height than the main inlet opening, molding strips secured to the floor between which the lower portions of the removable section at 5 the sides of the air opening are engaged, a plurality of eyes secured to the rear face of the section adjacent the opening therein, the casing comprising a sheet metal wall from which adjacent pairs of openings are cut to 10 form intervening metal strips, and turnbuckles having hooked ends engageable with the strips and eyes respectively.

18. In combination with a concealed radiator assembly comprising a casing positioned within a wall recess there being an inlet opening leading to the recess through the inner wall sheathing of the room adjacent the floor, and a radiator mounted in the casing and removable through the inlet opening, a removable baseboard section forming a portion of the continuous baseboard of the room, the ends of the removable section being beveled inwardly from the front face of the section to mate with the 20 outwardly beveled ends of the adjacent fixed baseboard sections, said removable section covering the inlet opening and being cut away in its lower central portion to form an air inlet of less length and height than the main inlet opening, molding strips secured to the floor between which the lower portions of the removable section at the sides of the air opening are engaged, a plurality of eyes secured to the rear face of the section adjacent the 25 opening therein, the casing comprising a sheet metal wall from which adjacent pairs of openings are cut to form intervening metal strips, and springs having hooked ends engageable with the strips and eyes respectively.

19. In combination with a concealed radiator assembly comprising a casing positioned within a wall recess there being an inlet opening leading to the recess through the inner wall sheathing of the room adjacent the floor, and a radiator mounted in the casing and removable through the inlet opening, a removable baseboard section forming a portion of the continuous baseboard of the room, the ends of the removable section being beveled inwardly from the front face of the section to mate with the outwardly beveled ends of the adjacent fixed baseboard sections, said removable section covering the inlet opening and being cut away in its lower central portion to form an air inlet of less length and height than the main inlet opening, molding strips secured to the floor between which the lower portions of the removable section at the sides of the air opening are engaged, and means removably engaged between the rear face of the removable section and the rear wall of the recess for holding the section in position over the inlet opening.

20. In combination with a concealed radiator assembly comprising a casing posi-

tioned within a wall recess and having an inlet opening projecting through the inner wall sheathing of the room adjacent the floor, and a radiator mounted in the casing and removable through the inlet opening, a removable baseboard section forming a portion of the continuous baseboard of the room, the ends of the removable section being beveled inwardly from the front face of the section to mate with the outwardly beveled ends of the adjacent fixed baseboard sections, said removable section covering the inlet opening and being cut away in its lower central portion to form an air inlet of less length and height than the main inlet opening, molding strips secured to the floor between which the lower portions of the removable section at the sides of the air opening are engaged, a plurality of eyes secured to the rear face of the section adjacent the opening therein, the casing comprising a sheet metal wall from which adjacent pairs of openings are cut to form intervening metal strips, and springs having hooked ends engageable with the strips and eyes respectively.
